GALLEY LOCK

Webster G. Wiley, Glendale, Calif.

Application May 29, 1940, Serial No. 337,931

5 Claims. (Cl. 276—43)

This invention relates generally to locking or retaining devices for holding work such as type, spacer blocks and the like in printers' galleys, and particularly to a type of lock adapted to retain the work against longitudinal movement in the galley toward its open end. My primary object is to provide an improved form of galley lock that is reduced to the utmost simplicity and lowest cost, and at the same time capable of greater facility and efficiency in use than any form of lock heretofore devised for this purpose. This application is a continuation in part of my copending application Serial Number 314,067, filed January 16, 1940 for Galley lock.

In the past, many different forms of galley locks have been proposed, and some of these have met with varied commercial successes. Some have been adapted to be inserted between the work and a side flange of the galley, and functioning to hold the work by pressure laterally against it. As indicated above, the present lock is designed to prevent longitudinal displacement of the work within the galley by exerting end pressure against the work facing the open end of the galley. Insofar as I am aware, no satisfactory lock of this latter type has heretofore been developed, due to the fact that the proposed forms either have not been capable of the facility of use demanded by the printing trade, or because of other limitations such as excessive cost or inadaptability to all forms and sizes of galleys.

The present invention has been made with the object of reducing the lock to the simplest and most inexpensive form, and one which has such facility and efficiency in use as to satisfy the practical requirements of the trade. The invention may be described generally as providing a locking element in the form of a flexible member adapted to be inserted in flexed condition between the side flanges of the galley, and by virtue of its flexed condition, to frictionally engage the flanges and to bear intermediate its ends against the work to retain the work within the galley. In its preferred form the locking element consists of an elongated resilient metal strip of greater length than the distance between the galley side flanges, and applied by flexing one end portion of the strip away from the work so that the ends of the strip frictionally engage the flange and the section of the strip beyond its flexed portion bears flatly against the work.

One highly important feature of the invention is the determination of the degree of resiliency and flexibility that the locking strip should have for most satisfactory use and results. I have

found from considerable observations and tests that for greatest facility in use and to have the necessary flexure characteristics for most effectively engaging and retaining the work, the locking element should be made of a material, preferably though not necessarily steel, of substantial thickness and having at that thickness less than complete resiliency. That is to say, the resiliency of the metal should be such that, for example, when removed from the galley, the locking element will straighten to a considerable degree but will not return to its original (referred to as normal) perfectly straight form. The reasons for giving the locking element these characteristics of resiliency and flexibility can later be described to better advantage.

The various features and objects of the invention referred to in the foregoing will be more fully understood from the following detailed description of the invention as embodied in a typical and illustrative form. Reference is had throughout the description to the accompanying drawing in which:

Fig. 1 is a perspective view showing a conventional form of galley with the work held therein by the locking strip; and

Fig. 2 is a perspective view of an unflexed locking strip.

In Fig. 1 I show a typical form of double-column galley, generally indicated at 10, comprising a plane surface bottom 11 having upwardly projecting parallel side flanges 12 and an end flange 13. As will be understood, the galley may contain any suitable assembly of work including various arrangements of type, or combination type and spacer blocks. The work is shown conventionally as consisting of two columns 14 of type spaced at 15 from one side of the galley. The invention of course is independent of any particular size galley, being applicable to either single or double column galleys and in general to various size galleys ranging, for example, from 3½ to 12 inches in width. The length of the locking element to be used in any given instance will of course be predetermined in accordance with the width of the size galley to which it is to be applied.

The locking element 16 consists of an elongated resilient and flexible element made preferably of strip steel of selected and predetermined composition and properties, the length of the strip being substantially greater than the distance between the galley side flanges 12. The height of the locking strip, as viewed in the drawing, may correspond substantially to the depth of the galley,

and ordinarily the strip, while relatively thin, will have substantial thickness, say from 0.030 to 0.050 inch.

In applying the lock, the strip first may be placed in the dot-dash position 16a and then flexed to the solid line position by pressing against the strip at a point toward the end portion 16b to be flexed. When fully inserted, the strip by reason of its flexed condition exerts an endwise thrust against the galley flanges 12, whereby causing the end of the strip to frictionally engage the flange surfaces, and also causing the greater length of the strip, represented by the portion 16c between the bend 16d and its opposite end 16e, to press flatly and tightly against the work 14. When thus inserted in the galley, the locking element remains securely in place, exerting such pressure against the work as to cause the work to be confined between the locking element and the galley end flange 13, so securely as to prevent lateral shifting of the work toward the surface 15.

As previously mentioned, it is important that the locking strip have certain characteristics of resiliency and flexibility to enable it to be used with facility and to flex in a manner to best conform with the work. To illustrate, it has been found that where an extremely resilient and less flexible strip is used, such as one made of highly tempered or the ordinary spring steel (that has an elastic limit usually in excess of 150,000 lbs. per sq. in.), the strip when flexed into locking position against the work exerts such great end pressure against the flanges 12 as to render it difficult to remove the lock. For the same reason it is relatively difficult, with that type of steel, to flex the strip into locking position and to maintain the desired length of flat engagement at 16c between the strip and the work, due to the tendency of the steel to assume longer curvature at the flexed portion 16d. A further practical disadvantage is encountered in that the harder and more tempered steels are difficult to cut to the proper strip lengths with their ends smoothed, as they should be, to permit sliding engagement with the galley flanges.

Far superior results have been obtained by making the locking strip of a metal that has limited or less than full resiliency, and which is relatively easily flexed. For example I may use tool or crucible steel in the "as rolled" condition, and therefore of a tough or fibrous structure, having an elastic limit or yield point within the range of 80,000 to 130,000 pounds per sq. in. I have used to advantage crucible steels within different ranges of elastic limit, having a carbon content within substantially the range of 0.90 to 1.10, and a Rockwell hardness of substantially C23 to 28. Metal within the elastic limit range contemplated, has the advantage of rendering the locking element capable of easy insertion in and removal from the galley, and yet enabling the element to bear against the galley and work with full effectiveness. Although it bends with relative ease, and retains some though not all of its deformation when removed from the galley, the locking strip readily assumes its proper flexed shape when again placed in the galley.

I have previously referred to the fact that the metal strip by reason of its limited or less than full resiliency, will retain a considerable degree of its flexed deformation after removal from the galley. As a measurement of such retained deformation, it has been found that when re-

moved from the galley, the flexed end portion 16d will retain a degree of deflection relative to the straight portion 16c, within 5° to 15° (measured on the basis of the angularity between a line connecting the end extremity of the strip and the point at which the effected end portion starts to curve, and the projected line of the straight portion 16c). The retained deformation of a given locking strip will of course vary somewhat with the length of time the strip has remained in flexed condition within the galley, but in general the retained deformation will lie within the angular limits stated. Being tough and preferably untempered, the steel will stand constant use without crystallizing and remain capable of applying and withstanding considerable pressures. Since it is adapted to greater ease in bending, a longer surface of the strip at 16c can be maintained in contact with the work and the locking effect of the strip correspondingly increased. By reason of its limited resiliency, the locking strip does not tend to bite into the galley flanges with such force as to be difficultly removable, and because of the superior workability of this type of steel, the strip stock can more readily and economically be cut and the ends smoothed to give proper sliding contact with the galley flanges.

Practical tests and use of these locking strips 30 has established their ease in handling and facility of use, as well as their adaptability to extremely low manufacturing costs. By making the locking element in a straight strip form, advantages are obtained not only with respect to 35 ease and economy in manufacture, but also in the locking action and effectiveness of the strip. With the strip normally in straight form, as distinguished for example from a normally curved or bent form, a greater end thrust is transmitted 40 to the galley flanges when the strip is flexed, by reason of the longitudinal rigidity of the metal. Thus, in this manner, maximum gripping force is obtained using a metal of given resiliency, and at the same time provision is made for rendering the strip easily removable, by using a metal of 45 limited resiliency. While I have referred to the locking strip as normally being straight, it will be understood of course that the locking elements once used will have some retained curvature at the flexed end. When reused, such strips ordinarily will be inserted within the galley so as to be flexed into locking position oppositely from the retained flexure of the previous use. Thus the locking element becomes reversible in use, a feature possessed by no other similar devices of which I am aware.

I claim:

1. A lock adapted to hold work in a galley having inwardly facing side surfaces, said lock 60 consisting of a normally straight element substantially longer than the distance between said surfaces and made of metal of about 0.030 to 0.050 in. thickness having an elastic limit between 80,000 to 130,000 pounds per sq. in., said element being adapted to be inserted in flexed condition between said galley surfaces and, by virtue of its flexed condition, to frictionally engage the surfaces and bear intermediate its ends directly against the work, and said element having substantially less than complete resiliency to facilitate its removal from between said surfaces, such that when removed the element will retain a considerable degree of its flexed deformation.

2. A lock adapted to hold work in a galley

having inwardly facing side surfaces, said lock consisting of a normally straight flat strip element substantially longer than the distance between said surfaces and made of untempered steel in the "as rolled" condition and having an elastic limit between 80,000 to 130,000 pounds per sq. in., said element being adapted to be inserted in flexed condition between said galley surfaces and, by virtue of its flexed condition, to frictionally engage the surfaces and bear intermediate its ends directly against the work, and said element having substantially less than complete resiliency to facilitate its removal from between said surfaces, such that when removed the element will retain a considerable degree of its flexed deformation.

3. A lock adapted to hold work in a galley having inwardly facing side surfaces, said lock consisting of a normally straight metallic strip element substantially longer than the distance between said surfaces and within about 0.030 to 0.050 in. thickness, said element being adapted to be inserted between said galley surfaces with one end only of the element in flexed condition to cause the element to frictionally engage the surfaces and bear directly against the work, said element having substantially less than complete resiliency to facilitate its removal from between said surfaces, such that when removed said flexed end of the element will retain between 5° to 15° of its flexed deformation.

4. A lock adapted to hold work in a galley having inwardly facing side surfaces, said lock

consisting of a normally straight element substantially longer than the distance between said surfaces and made of untempered steel having an elastic limit between 80,000 to 130,000 pounds per sq. in., said element being adapted to be inserted between said galley surfaces with one end only of the element in flexed condition to cause the element to frictionally engage the surfaces and bear directly against the work, 10 said element having substantially less than complete resiliency to facilitate its removal from between said surfaces, such that when removed said flexed end of the element will retain between 5° to 15° of its flexed deformation.

15 5. A lock adapted to hold work in a galley having inwardly facing side surfaces, said lock consisting of a normally straight element substantially longer than the distance between said surfaces and made of strip metal of about 0.030 to 0.050 in. thickness having an elastic limit between 80,000 to 130,000 lbs. per sq. in., said element being adapted to be inserted between said galley surfaces with one end only of the element in flexed condition to cause the element 20 to frictionally engage the surfaces and bear directly against the work, said element having substantially less than complete resiliency to facilitate its removal from between said surfaces, such that when removed said flexed end of the element will retain between 5° to 15° of its flexed deformation.
